UNITED STATES PATENT OFFICE.

JACOB IRSCH, OF NEW YORK, N. Y.

GAME OF SKILL.

Application filed March 19, 1921. Serial No. 453,613.

To all whom it may concern:

Be it known that I, JACOB IRSCH, a citizen of the United States, and a resident of the city of New York, borough of Manhattan, in the county of New York and State of New York, have invented a new and Improved Game of Skill, of which the following is a full, clear, and exact description.

This invention relates to games of skill and particularly to an improved game which is intended to be amusing when two or more play at the same time.

Another object of the invention is to provide a game of skill or amusement device wherein steadiness of motion by the operator determines the chances of winning the game.

A still further object of the invention is to provide an amusement device wherein all parts are visible so that contestants may readily see how his own part and the parts of others are progressing.

In the accompanying drawings—

Figure 1 is a front view of the complete apparatus or outfit illustrating one embodiment of the invention.

Figure 2 is a transverse sectional view through Figure 1 approximately on line 2—2.

Figure 3 is an enlarged fragmentary sectional view showing certain of the operated parts disclosed in Figure 2.

Figure 4 is a diagram showing the electric wiring forming certain parts of the invention.

Referring to the accompanying drawings by numerals 1 indicates a housing or shed which is provided with a counter 2 and on which is mounted an annunciator 3 of usual construction designed to disclose a number 35 when the circuit is closed for that particular number. A suitable cord 4 is connected with the annunciator 3 so that the attendant may re-set the annunciator at any time. Arranged above the counter 2 are a number of 40 knobs or discs 5 which are numbered as indicated in Figure 2 and said discs are supported by cables 6 passing over pulleys 7 and 8. Each cable 6 is connected with a spring 9 and said spring is connected to a 45 clamping band 10 secured to a figure of a fowl 11 which may be a duck, goose or other

desired fowl. The band 10 has a hook 12 pivotally connected therewith and is normally held in a given position by spring 13 secured to the floor in any suitable manner. The figure 11 is pivotally mounted at 55 14 on a suitable support so as to freely swing back and forth when positively actuated but which is normally held in the position shown in Figures 2 and 3 when not 60 being operated. By pulling on the cord 6 the figure may be tilted to the dotted position shown in Figure 3 or to a number of intermediate positions.

The figure is preferably formed of glass 65 though it may be made of other material and is provided with an inlet opening and a discharge or outlet opening 16. A suitable ball 17 of any desired material is provided, said ball being preferably rather 70 heavy. A baffle or obstacle 18 is arranged within the body of the figure so that the figure must be jarred back and forth or rather upwardly and downwardly so as to cause the ball to be projected over the obstacle 18 and later through the opening 16. In order to assist this action the ball 17 may 75 be made from hard vulcanized rubber and when so made may be covered by paint of any desired color.

In pulling on the cable 6 a spring 9 will move slightly while spring 13 will give more or less freely whereby an up and down movement of the figure may be secured. When it is desired to stop the movement of the 80 figure the locking bar 19 is allowed to move over to the position shown in Figure 3, said movement being caused by the spring 20. This locking bar 19 is provided with a depending end section 21 at each end, which 85 end section is pivotally supported in any suitable manner. A cord or other suitable member 22 is connected to the bar 19 and extends to a position near the counter 2 so that whenever any one desires to operate 90 any of the cords 6, the attendant may release the various figures 11 by pulling on the cord 22 and holding the locking bar 19 out of engagement with the various hooks 12. As soon as the game has been completed cord 95 22 is released and bar 19 will automatically interlock with hook 12 so as to prevent any 100

- further movement of the figures. If any one should pull on the cable 6 after the hook 12 has been locked, said pulling will merely stretch to a certain extent the spring 9.
- 5 In the drawing twelve cords 6 have been shown and twelve figures 11 but a greater or less number may be used if desired. When one or more of these figures have been operated and the ball 17 from one of the 10 figures discharged out through opening 16, it will fall into the trough 23 adjacent that particular figure and will roll down and strike the spring contact 24 and press the same against the stationary contact 25 for 15 closing an electric circuit. The first ball which closes the electric circuit acts as a winning ball and the person causing said ball to be discharged from the figure will be the winner of that particular game.
- 20 In Figure 4 will be seen a diagram of the circuit connected with the contacts 24 and 25. The various contacts 24 and 25 are connected by suitable wires to the various annunciator mechanisms on board 26. As 25 there are twelve troughs 23 there will be twelve annunciator members 27 on board 26, namely, one for each of the troughs 23. It will be noted that the common return 28 is connected to an electric magnet 29 so that 30 when in contact any of the troughs 23 are closed the magnet 29 will be operated and move the keeper 30 to the dotted position shown in Figure 4. This keeper is provided with a shoulder 31 acting to normally hold 35 the contact arm 32 in engagement with the contact 33 whereby the circuit of the magnet 29 is closed at this point. The common return from the contact lever 32 extends to the source of current 34. In order that the 40 action will be more evident the circuit of one of the annunciator members 27 will be traced. For instance, if the ball drops into the first trough 32 and thereby closes the circuit in said trough the annunciator 27 45 marked 1 will be actuated for indicating the number on the board 26. When the circuit is closed in this manner current will pass from the source 34 to the common supply wire 35 and from thence to the contact member 24. From contact 24 the current will pass to contact 25, wire 36, annunciator structure 27 indicated as one, common return wire 28, magnet 29, contact 33, contact lever 32 and wire 37 back to the source 34. 50
- 50 As soon as the contacts 24 and 25 engage this circuit will be closed and magnets 29 energized for moving the keeper 30 away from the lever 32. As soon as this has been done lever 32 will fall under the action of 55 gravity and engage the contact 38 where upon the circuit of the bell 39 will be closed and will remain closed until the operator pulls the cord 40 back to its former position where upon the keeper 30 will fall by grav-

ity so that the shoulder 31 will interlock 65 with lever 32 and hold the lever in engagement with contact 33.

By reason of the circuits shown in Figure 4, the first ball which closes the circuit will cut out of the circuit all other balls until 70 the lever 32 has been manually restored. In this way there can be only one winner even though the second ball may be only a very short distance in back of the first ball. Before the operator stops the bell he releases 75 cord 32 so that the various figures 11 are locked against movement and he then restores the lever 32. The ball which has been discharged is then restored to the figure through the opening 15 and the device is 80 ready to play a second game.

It will be understood that the various annunciator structures 27 on the board 26 are of any usual or preferred kind so as to either raise or lower the member to bring 85 the same to view. The only special feature is the arrangement of the magnet 29, lever 32 and associated parts together with the other particular wiring not forming any part of the annunciator itself. 90

In order to play the game any desired number of persons may play at the same time not exceeding twelve for the structure shown. Each player grasps the particular rope or cord 6 selected and when the signal 95 is given by the operator the players begin to give the various ropes slight jerks or pulls for rocking the various figures 11 so as to cause the balls 17 to jump over the obstacles 18. After this operation has been done the 100 rope is pulled rather quickly and for a considerable extent to cause the various balls to be projected toward the head of the figure sufficiently for causing the ball to pass out the discharge opening 16. The first ball 105 which is discharged out the opening and reaches the contact 24 will close the circuit of that particular contact and will win the game. Even though two balls are in certain 110 of the troughs 23 only one will win and that one will be the ball which is nearest to its particular contact 24. In order that the figures 11 may be always held in a certain position when not actuated a knot or stop 37 is provided for each cord 6. 115

What I claim is:—

1. An amusement device of the character described comprising a plurality of hollow figures each having an opening, a ball arranged in each of said figures, manually actuated means connected with the figures whereby the figures may be manually agitated so as to cause the ball to be discharged through said opening, a signal member, means for actuating said signal member and means for directing said ball to a position for causing said actuating means to operate. 120

2. An amusement device comprising a

- plurality of hollow figures, each of said figures having an opening, a ball arranged in each of said figures, a manually actuated member connected with each of said figures, a guiding trough for each of said figures for receiving the ball therefrom when the figures have been moved to a predetermined position and means actuated by the respective balls for producing a signal.
- 10 3. An amusement device of the character described comprising a plurality of hollow figures, each figure having an opening, a ball arranged in each figure capable of passing through said opening, a spring for each 15 of said figures for normally holding the same in a given position, a manually actuated member connected with each of said figures for moving the same against the action of said spring so as to discharge said ball from said opening, a signal member and means for receiving the balls from the respective figures and guiding the same to a point for causing the actuation of said signal.
- 20 4. An amusement device of the character described comprising a plurality of hollow figures, each of said figures having a discharge opening, a ball arranged in each of said figures, a spring for normally holding 25 each figure in a given position and a flexible manually actuated member connected with each of the figures whereby said figures may be actuated for causing the balls therein to be discharged through the openings in 30 the figures.
5. An amusement device of the character described comprising a plurality of hollow figures, each figure having a discharge opening and a baffle at a distance from the discharge opening, a ball arranged in each of said figures on the side of the baffle opposite the discharge opening, a spring connected with each of said figures for holding the same in a given position and manually actuated 40 means connected with each of said figures for permitting the movement of the figures so as to cause the said ball to jump over said baffle and be discharged out said opening.
- 45 6. In an amusement device of the character described a plurality of hollow figures, each of said figures having a discharge opening and a baffle arranged a distance from the discharge opening, a ball arranged in each 50 of said figures on the opposite side of said baffle to the discharge opening whereby the balls must pass over the baffle before they can move out the discharge opening, a spring connected with each of said figures for re- 55 silently holding the figures in a given position, manually actuated means for causing the figures to be moved so as to discharge the balls therein out said openings and manually disconnected locking means for locking si- 60 multaneously all of said figures against movement by said manually actuated means.
7. In an amusement device of the character described a plurality of hollow figures, each figure having an opening and a baffle arranged in the figure, manually actuated means for moving said figures independently for causing the balls therein to be discharged out said opening, a hook carried by each of said figures, a spring for each of said hooks for holding the same normally in a given position and also holding the figures in a given position, a swinging bar extending across all of the hooks, means for causing said bar to normally remain interlocked with said hooks and manually actuated means for moving said bar out of engagement with said hooks.
8. In an amusement device of the character described a plurality of hollow figures, a ball arranged in each of said figures, each of said figures being formed with a discharge opening, manually actuated means for moving said figures independently so as to cause the balls to discharge out said opening, an independent trough for each of said figures for receiving said balls, an electric switch arranged in each of said troughs positioned to be closed by said balls as they move out of said trough, a sounding device, means for causing the sounding device to operate and means including said switch for causing the actuation of the means which operates the signal device.
9. In an amusement device of the character described a plurality of hollow figures having discharge openings, a ball arranged in each of said figures, manually actuated means for moving the figures so as to discharge said balls through said openings, an independent trough for receiving each of said balls, said troughs being arranged on an incline so that the balls will roll to the lower end of the respective troughs, a switch arranged at the lower end of each of said troughs adapted to be closed by the respective balls as they reach the lower end of the troughs, a signal device and means for causing the signal device to operate, said means including a circuit of which said switch is a part.
10. In an amusement device of the character described a plurality of hollow figures, each being provided with a discharge opening, a ball arranged in each of said figures, and manually actuated means for independently moving said figures for causing the balls to be discharged through said opening, an inclined trough for each of said figures for receiving the balls therefrom, an electric switch adjacent the lower end of each of said troughs adapted to be closed by the respective balls as they reach the lower end of the trough, a signal device and means including said switch for causing the signal device to operate.

device to be operated, said means also including a cutout for automatically cutting out said switch and all of the remaining switches in the other troughs, whereby the signal may be produced by only one ball.

11. An amusement device comprising a plurality of hollow figures, each of said figures having an opening, a member arranged loosely in each of said figures, a guid-

ing member arranged adjacent each of the figures for receiving a member loosely positioned therein when said hollow figures have been moved to a certain position, and manually actuated means connected with each of said figures for moving the figures so as to discharge the member arranged therein.

JACOB IRSCH.
